HOUSING FOR A BATTERY PACK FOR USE WITH A DATA COLLECTION TERMINAL AND THE LIKE

William R. Goodale, Claremont, and Ronald E. Loosen,
Malibu, Calif., assignors to MSI Data Corporation,
Costa Mesa, Calif.

Filed Dec. 13, 1972, Ser. No. 314,698

Term of patent 14 years

Int. Cl. D13—02

U.S. Cl. D26—15 A

Fig. 1

Fig. 2

Fig. 3

Fig. 4

Fig. 6

Fig. 7

Fig. 5

FIG. 1 is a front perspective of a housing for a battery pack for use with a data collection terminal and the like showing our new design;

FIG. 2 is a front elevation thereof;

FIG. 3 is a rear elevation thereof;

FIG. 4 is a right side elevation thereof;

FIG. 5 is a left side elevation thereof;

FIG. 6 is a bottom plan view thereof; and

FIG. 7 is a top plan view thereof.

We claim:

The ornamental design for a housing for a battery pack for use with a data collection terminal and the like, as shown.
